UNITED STATES PATENT OFFICE.

HARRY J. SMITH, OF BELLEVUE BOROUGH, PENNSYLVANIA.

VENTILATING DEVICE.

1,402,101.

Specification of Letters Patent.

Patented Jan. 3, 1922.

Application filed March 31, 1920. Serial No. 370,122.

To all whom it may concern:

Be it known that I, HARRY J. SMITH, citizen of the United States, and residing in the borough of Bellevue, in the county of 5 Allegheny and State of Pennsylvania, have invented or discovered new, useful, and Improved Ventilating Devices, of which the following is a specification.

My invention consists in certain new and 10 useful improvements in ventilating devices.

In the case of bed rooms in private homes, and also in hospital rooms, ventilation, especially at night, by the admission of air through an unobstructed or wire screened 15 open window, is not recommended by physicians, especially in cases where there is a tendency to bronchial or pulmonary troubles, or, generally, in the case of delicate or aged persons.

20 Physicians recommend that the air be filtered through a screen of coarse cheese-cloth, muslin or other fabric. The present practice is to tack the fabric over a frame which is set in the window frame under the 25 edge of the partially opened sash.

The fabric, especially in cities, quickly becomes soiled and unsightly owing to the deposit of soot and dust from the entering air, which deposit also in time clogs the 30 interstices in the material and thus renders the latter more or less impervious.

Thus the material must at frequent intervals be removed from its frame and a clean 35 piece substituted, an operation which, owing to its tediousness, and which in a hospital containing hundreds of beds is a stupendous undertaking, is generally neglected.

Also, it is customary to filter the air admitted from the outside atmosphere to a 40 hot air furnace or other house or building heating or ventilating system, and such screens, generally formed of cheese-cloth, muslin or some other fabric, should be frequently renewed if the air is to be freely 45 admitted and effectually filtered.

Many other instances of like character will suggest themselves to one acquainted with the art.

The object which I have in view is the 50 provision of convenient means whereby the soiled material may be removed from service and clean material substituted by a simple operation requiring no removal or replacement of tacks, nails or screws, and in

a moment of time, so that an attendant may 55 quickly and at stated intervals renew the ventilating screens in a large hospital, or other building, or the nurse or attendant of an invalid may, whenever deemed necessary, quickly substitute fresh, clean material for the soiled material displaced. 60

For this purpose, I have provided a pair of rollers, one a dispensing roller and the other a receiving roller, and said rollers are mounted on either side, preferably at 65 the top and bottom of the opening through which the air is to enter, such, for instance, as the opening made in a window by raising the lower sash or lowering the upper sash. The dispensing roller has mounted 70 therein a roll or supply of cheese cloth or other suitable material and the loose end of said material is attached to the receiving roller, being thus extended across the opening which it is desired to screen. 75

Thus, by winding up the material on the receiving roller and accordingly unwinding it from the dispensing roller at proper intervals, a length of material which has occupied the ventilating opening until it has 80 become fouled, may be wound up out of the way on the receiving roller, and a fresh and clean length exposed for service.

For convenience, I prefer to mount the roller on the top and bottom bars of a frame 85 which fits in the window frame, or other opening, and in the case of a window frame, either below the partially or wholly raised lower frame or above the partially or wholly lowered upper frame. 90

I also provide means for holding the exposed length of material snug and flat against the ventilator frame.

I also prefer to provide the ventilator frame with wire screening, which should be 95 at the outside of the cheese cloth to protect the same, and also to enable the frame to be used as a wire screen with the cheese cloth omitted, if desired.

In the case of large openings, I prefer 100 to support the fabric on both sides.

I prefer to use a spring roller for the dispensing roll to prevent excess unwinding of the material, the receiving roller being provided with means for conveniently rotating it to wind up the material, and also with means to prevent unwinding rotation of the receiving roll. 105

Other novel features of construction and arrangement of parts will appear from the following description.

In the accompanying drawings, which are merely intended to illustrate a practical application of the principles of my invention to window ventilation, without limiting the scope thereof to the construction shown, Fig. 1 is an inside elevation of a window fitted 5 with my improved ventilator which is inserted in position under the partially raised lower sash; Fig. 2 is a vertical section taken along the line II—II in Fig. 1; Fig. 3 is an elevation showing the ventilator frame 10 removed from the window, and the rollers and cheese cloth are also omitted; Fig. 4 is a broken end view of the ventilator frame looking toward the left in Fig. 3, the lower roller being shown in place, and Fig. 5 is a 15 broken perspective showing a corner of the stretcher used to hold the exposed breadth of material tautly on the frame.

The following is a detailed description of the drawings.

25 A represents a window frame in which are mounted the usual lower sash B and upper sash C slideable in vertical planes.

In Fig. 1 the lower sash B is shown partially raised and D is the ventilator frame 30 inserted in the window frame under the bottom rail 1 of the lower sash B.

The frame D may be of wood or metal as may be desired, and may fit the window frame snugly, if desired. I prefer however 35 to form one end bar of the frame D with an upwardly and inwardly inclined vertical edge, so that a reversely inclined wedge member 2 may be used to fit the frame D snugly in the window frame and to permit the convenient removal of the frame D from the 40 window frame when desired. Thus by providing wedge members 2 of various widths, the frame may be fitted into window frames of a relatively wide range of widths, thus 45 enabling me to place on the market a standard length, or possibly a small number of standard lengths of the ventilation frame which can be used in windows of practically any size.

50 The bars of the frame D are preferably provided with a rabbet 3 along their inner edges at outside of the frame for the wire screen 4 which may be held in place by the molding 5, thus providing a convenient insert screen for the window. The wire screen also aids in holding the fabric in place, and when intended for this purpose only a coarse wire grid or simply vertical or horizontal bars or wires may be substituted.

55 At either end of the frame D and at the top and bottom, I provide on the inner face of the frame the bearing brackets 6.

E is a roller, which I call the dispensing roller, journaled horizontally in the top 60 brackets 6 and F is a second roller, which I

call the receiving roller, journaled in the lower brackets 6. The dispensing roller E is preferably provided with means to retard its rotation, which may be in the form of a suitable spring mechanism 7.

I have shown the dispensing roller at the top of the frame and the receiving roller at its bottom, but it will be understood that their positions may be reversed, or they may be vertically disposed at either end of the 75 frame D.

The dispensing roller E is provided with a web or relatively long length of cheese cloth G or other suitable fabric whose outer or free end is led across the inner face of 80 the frame opening and attached by any convenient means to the receiving roller F, and thus, when the exposed portion of the material becomes fouled from continued use, the receiving roller may be rotated to wind 85 up the material thereon until a fresh portion of the material G is unwound from the roller E and exposed on the frame D.

For convenience in rotating the receiving roller to wind up the soiled material, I provide means which may be conveniently grasped, such as the finger knob 8 on the end 90 of the roller shaft, and to prevent the roller F from being reversely rotated, thus unwinding the soiled material stored therein, 95 I prefer to provide the roller shaft with a ratchet wheel 9 which is engaged by a trailing pawl 10 mounted on the frame D.

When the material has been unwound from the dispensing roller onto the receiving 100 roller, both rollers are dismounted, and a fresh loaded dispensing roller and empty receiving roller substituted, the fouled material being removed from the dismounted receiving roller and after being laundered, 105 rewound on the dispensing roller for reuse.

It is desirable to have the material G stretched snugly over and tightly against the inside surface of the frame D so that it will present a neat appearance, and also that all 110 the entering air will be forced to pass through the material. Thus the material should be of sufficient width to more than span the opening in the frame D, so that when it is held taut and snug against the 115 frame, it will fully cover the entire opening in the frame.

Any convenient method may be used to stretch and hold the material in place. Thus, I have shown the inner face of the frame D provided with a groove or seat 11 spaced 120 from the inner edge of the frame and running around the same in the form, preferably, of a parallelogram, and H is a stretcher of similar contour and preferably pressed 125 of more or less resilient metal adapted to fit against the inner face of the frame D, with the material G interposed between the stretcher and the face of the frame D, the stretcher H being provided with an angular 130

boss or rearward shoulder 12 which is adapted to be sprung into the seat 11 carrying with it the material G. Thus the portion of the material exposed is stretched taut and snugly against the inner face of the frame D, completely closing the opening and better enabling the material to permit the passage of the air therethrough. Of course, the stretcher H is removed before a fresh portion of material is unwound from the dispensing roller and disposed across the face of the frame D, and the stretcher is then replaced to properly stretch the exposed material.

The material should be of sufficient width to be properly engaged by said stretcher, the stretcher preferably covering and concealing the edges of the material, which edges need not, therefore, be hemmed or finished, as the torn or raw edge is protected and concealed from view.

Thus the lengths of material to be used in the ventilators may be quickly and cheaply prepared by tearing strips of the proper width from the commercial pieces.

Where the ventilating opening is relatively large, I find it advantageous to provide the frame H with one or more horizontal or vertical cross bars 13 which bear against the inner face of the exposed material G and prevent inward bulging and possible rupture of the material on a windy day or under the influence of a strong ventilating fan or other suction device.

Such bars also coat with the screen or bars on the outside of the frame D to hold the material flat.

It is evident from the foregoing that my invention is highly advantageous for many uses, such as in window and other ventilating openings. It may also be used as a concealing screen in the window of doctors' and dentists' offices where ventilation which does not sacrifice privacy is desired.

What I desire to claim broadly is:—

1. A ventilator of the character described and adapted to be inserted in the ventilating opening, comprising a frame, a pair of rollers journaled on opposed bars of said frame, a length of ventilating material wound on one of said rollers with its outer end led across said frame and attached to the other roller, whereby when the portion of said material exposed between said rollers becomes fouled, the soiled portion thereof may be wound up on the second roller and a fresh portion unwound from said first named roller and exposed on said frame, and means for stretching the exposed portion of said material snugly against said frame.

2. A ventilator of the character described and adapted to be inserted in the ventilating opening, comprising a frame, a pair of rollers journaled on opposed bars of said frame, a length of ventilating material wound on

one of said rollers with its outer end led across said frame and attached to the other roller, whereby when the portion of said material exposed between said rollers becomes fouled, the soiled portion thereof may be wound up on the second roller and a fresh portion unwound from said first named roller and exposed on said frame, and a stretcher for holding the exposed portion of said material taut and snug against said frame.

3. A ventilator of the character described and adapted to be inserted in the ventilating opening, comprising a frame, a pair of rollers journaled on opposed bars of said frame, a length of ventilating material wound on one of said rollers with its outer end led across said frame and attached to the other roller, whereby when the portion of said material exposed between said rollers becomes fouled, the soiled portion thereof may be wound up on the second roller and a fresh portion unwound from said first named roller and exposed on said frame, said frame being provided with a seat surrounding the opening in the frame, and a stretcher adapted to engage said seat to hold the exposed portion of said material taut and snug against said frame.

4. A ventilator of the character described and adapted to be inserted in the ventilating opening, comprising a frame, a pair of rollers journaled on opposed bars of said frame, a length of ventilating material wound on one of said rollers with its outer end led across said frame and attached to the other roller, whereby when the portion of said material exposed between said rollers becomes fouled, the soiled portion thereof may be wound up on the second named roller and a fresh portion unwound from said first named roller and exposed on said frame, and restraining means bearing on the edges of said exposed material to prevent inward bulging of the material.

5. A ventilator of the character described and adapted to be inserted in the ventilating opening, comprising a frame, a pair of rollers journaled on opposed bars of said frame, a length of ventilating material wound on one of said rollers with its outer end led across said frame and attached to the other roller, whereby when the portion of said material exposed between said rollers becomes fouled, the soiled portion thereof may be wound up on the second named roller and a fresh portion unwound from said first named roller and exposed on said frame, and means on either side of said exposed material to hold the same in proper position against the frame.

Signed at Pittsburgh, Pa. this 25th day of March 1920.

HARRY J. SMITH.
